UNITED STATES PATENT OFFICE.

DONALD S. BARROWS, OF ROCHESTER, NEW YORK, ASSIGNOR TO THE T. H. SYMINGTON COMPANY OF NEW YORK, N. Y., A CORPORATION OF DELAWARE.

JOURNAL BOX.

Application filed May 3, 1920. Serial No. 378,529.

To all whom it may concern:

Be it known that I, DONALD S. BARROWS, a citizen of the United States, residing at Rochester, in the county of Monroe and State of New York, have invented certain new and useful Improvements in Journal Boxes; and I do hereby declare the following to be a full, clear, and exact description of the invention, such as will enable others skilled in the art to which it appertains to make and use the same.

The invention relates to journal boxes for railway vehicles and more particularly to journal boxes which are provided with pivoted or hinged lids, and its primary object is to provide a simple, strong and reliable locking mechanism for maintaining the said lids in closed position, said mechanism being mounted on the said lids and so arranged with respect thereto as to completely close the lock receiving cavity therein and to thereby prevent the entrance of foreign matter into the said journal boxes.

To this end the main feature of the invention, generally stated, consists in providing a hinged or pivoted journal box lid with a spring actuated sliding locking mechanism and in so constructing the said lid as to provide the same with integral means for maintaining the locking mechanism in position, the said means being adapted to extend into the path of travel of the locking mechanism to prevent the loss of the same.

Another feature of the invention resides in providing a journal box lid of the type above described with a lock receiving cavity, the opening in the said cavity through which the locking mechanism is operated being adjacent to the lower edge of the said lid.

Another feature of the invention is to provide a journal box lid with a spring actuated locking mechanism and to arrange the mechanism so that the lock operating means or key when in operative position extends downwardly below the lower edge of the said lid to afford means for moving the lid against the pressure of the spring closing means with which this type of lid is provided.

Another feature of the invention consists in providing a locking lid of the type above described with an imperforate outer face.

To these and other ends the invention re-

sides in certain improvements and combinations of parts all as will be hereinafter more fully described, the novel features being pointed out in the claims at the end of the specification.

In the drawings which have been selected to illustrate my invention,

Figure 1 is a longitudinal sectional view of a portion of a journal box and associated lid, the latter having one form of my improved locking mechanism embodied therein.

Figs. 2 and 3 are elevational views showing, respectively, the inner and outer faces of the journal box lid illustrated in Fig. 1.

Fig. 4 is a perspective view showing a portion of the inner face of the improved lid illustrated in Fig. 1, the integral lock retaining means being shown in position to permit the insertion of a locking member within the locking recess.

Fig. 5 is a partial sectional view taken on line 5—5 of Fig. 1, the section being viewed in the direction indicated by the arrows at the ends of the said line.

Fig. 6 is a perspective view of the locking member.

Fig. 7 is a view similar to Fig. 1, showing a slight modification in the lock receiving cavity and illustrating also a portion of the lock operating means or key adapted for use with this form of lid; and

Fig. 8 is a fragmentary view illustrating a slight modification in the upper portion of the lock receiving cavity provided in the journal box lid.

Throughout the specification and drawings like parts are designated by like reference characters.

The journal box 1 may be provided with upwardly extending pivot ears or lugs 2, the said lugs having an opening 3 therein through which extends the pintle or hinge pin 4 of the journal box lid 5.

For convenience I have illustrated the lid 5 as provided with a well known type of spring mechanism 6 which is adapted to maintain the lid in closed position and which also assists in maintaining the lid in full open position. In the latter case the shoe 7, at the upper end of the spring member or mechanism 6, has been slid over the upper end of the hinged lug or pivot ears 2 and seats in a depression 8 which is provided on the upper surface of the lugs 110

2. Since this spring mechanism does not form a part of my invention it will not be necessary to further describe the same, although it is to be understood that this 5 form of spring mechanism is merely illustrated for convenience and my device may be used with other types of spring mechanism than the one shown.

The lid 5 has an intermediate portion 5^a 10 which extends at an angle to the side walls of the said lid, as will be clearly seen from the dotted lines 5^b in Figs. 1 and 7. A spring receiving recess or cavity 9 may conveniently be formed in the said lid by providing on the outer face of the lid a substantially rectangular projecting boss 10 and by continuing the side walls of the said boss on the interior or inner face of the lid, as clearly shown at 11. This recess 9 preferably 15 extends parallel with the side walls of the said lid 5 and at an angle to the intermediate portion 5^a so that the inner wall 12 at its upper portion is spaced away from the inner face of the portion 5^a. This portion of 20 the inner wall 12 at its upper portion is spaced away from the inner face of the portion 5^a. This portion of the inner wall 12 of the said recess is provided with a longitudinally extending slot 13, the purpose of 25 which will hereinafter be set forth.

The locking block 14 preferably comprises a body portion 15, which is shaped to conform to and closely fits within the recess 9, a locking lug 16 and a web 17 which serves 30 to connect the said lug to the body portion.

The slot 13 hereinbefore described is adapted to receive the web 17 of the locking block 14 and permits the necessary movement of the locking block from locked to 40 unlocked position. The purpose and object of extending this slot the full height of the said wall 12 is to permit the insertion of the locking block at the upper end of the said recess. To yieldingly maintain the lock in 45 locking position I provide a spring 18 which is interposed between the upper face of the said block and suitable abutments provided at the upper end of the said recess 9. These abutments may be formed either by providing 50 the inner wall 12 of the said recess with upwardly projecting tongues 12^a, which are clearly shown in Fig. 4, or by providing a plurality of rivets 12^b, as clearly shown in Fig. 8. In the form shown in Fig. 4 the 55 upwardly projecting tongues 12^a are relatively thin and narrow and are separated from the upper portions of the adjacent side walls 11 so that these tongues may be bent inwardly by any suitable means into a position substantially parallel with the said upper ends of the walls 11 after the locking block and spring 18 have been inserted within the recess 9. It will of course be understood that the spring 18 is placed under a 60 desired degree of compression by either

bending the tongues 12^a or by the insertion of the rivets 12^b so that the locking block will always be maintained in locking position. The locking lug extends below the lower face of the web 17 and is spaced from 70 the inner face 12 of the said lid a sufficient distance to enable the same to engage a lip 19 which is provided on the said journal box. In order to prevent the entrance of dust and dirt into the journal box a flange 20 may be 75 provided on the lid 5, the said flange being adapted to surround the edges of the opening in the front face of the said box 1.

It will be obvious that in the form of recess shown in Figs. 1 to 4, inclusive, the locking mechanism may be operated by the insertion into the lower end of the recess of any form of straight bar of sufficient strength to compress the spring 18 and to thereby move the locking block 14 upwardly 80 and out of contact with the lip 19. While this form of cavity possesses many advantages it is often desirable to provide a locking mechanism which cannot be operated except with a proper form of operating bar 85 or key, and my improved mechanism may be modified as clearly indicated in Fig. 7 to accomplish this desired result. Since the form of mechanism is identical with that shown in the other figures of the drawing, 90 it will be only necessary to describe the modification of the locking cavity for a complete understanding of this embodiment of the invention. The lower end of the cavity 95 21 instead of extending parallel or substantially parallel to the plane of the lid is turned at an angle thereto and preferably opens on the inner face of the said lid at a point below the flange 20, the outer wall of the said cavity being curved as clearly 100 shown at 22 to conform to this change of direction of the cavity. In this form of construction it is readily apparent that the locking mechanism cannot be operated by a straight bar since the opening at the end of 105 the cavity is not sufficient to permit a straight bar to be entered and angled so as to contact the locking block. I therefore provide a special form of operating bar or key 23 which is furnished intermediate its 110 ends, and preferably closely adjacent one end, with a cranked portion 24. The extension 25 of the bar is adapted to contact the lower face of the locking block, and the cranked portion is of sufficient width and 115 extent to permit the necessary movement of the bar to unlock the locking block 14.

Having now fully described my invention, what I claim and desire to secure by Letters Patent is:—

1. The combination with a journal box, of a lid pivotally connected thereto, a locking member slidably mounted in a recess provided in the said lid, and means integral with said lid for operatively connecting the 120 130

locking member thereto, said recess extending below the said locking member and being adapted to receive means for operating the said member.

6. 2. The combination with a journal box, of a lid pivotally connected thereto, said lid having a recess therein, the lower end of said recess being adjacent the lower edge of the said lid, a lock movably mounted 10 within the said recess, and means integral with the said lid and extending into the path of travel of said lock for preventing the accidental displacement of the said lock.

3. The combination with a journal box, 15 of a lid pivotally connected thereto, said lid having a lock receiving recess therein, a portion of a wall of said recess being adapted to be bent, a locking member within said recess, and a spring cooperating with said 20 locking member, the said portion of the wall engaging said spring and maintaining said locking member in operative position.

4. The combination with a journal box, 25 of a lid pivotally connected thereto, said lid having a lock receiving recess, a spring pressed locking member slidably mounted within said recess, one end of said recess opening adjacent the lower edge of the said lid, and adapted to receive means for operating said locking member.

5. The combination with a journal box, 30 of a lid pivotally connected thereto, a lock

receiving recess provided in the said lid, a lock insertable within said recess, one wall of said recess having a pair of spaced 35 tongues adapted to be bent after the introduction of the said lock to prevent the accidental displacement thereof.

6. The combination with a journal box, 40 of a lid pivotally connected thereto, said lid being provided with a lock receiving recess, a locking block within the said recess, one end of said recess opening below the lower face of the said locking block, the opposite end of the said recess opening on the inner 45 face of the said lid.

7. The combination with a journal box, 50 of a lid pivotally connected thereto, a lock receiving recess provided in the said lid, a locking block slidably mounted within the said recess, said recess having open ends, the said ends opening on the same face of the said lid, one of said open ends being adapted to receive means for operating said locking block.

8. The combination with a journal box, 55 of a lid pivotally connected thereto, said lid having an open ended recess therein, a locking member insertable within the said recess through one end thereof, and means integral with the said lid for closing the said end of the said recess.

In testimony whereof I affix my signature.
DONALD S. BARROWS.
